Primary Examiner — Rhea Shields

(57) **CLAIM**

The ornamental design for a biometric sensor, as shown and described.

DESCRIPTION

1. Biometric sensor
- 1.1 : Isometric view
- 1.2 : Top
- 1.3 : Bottom
- 1.4 : Right
- 1.5 : Left
- 1.6 : Front
- 1.7 : Back

1 Claim, 7 Drawing Sheets**1.1**
